DESIGN FOR A TABLE OR SIMILAR ARTICLE

Paul P. Cret, Philadelphia, Pa., assignor to Edward G. Budd Mfg. Co., Philadelphia, Pa., a corporation of Pennsylvania

Application February 3, 1939, Serial No. 82,755

Term of patent 14 years

To all whom it may concern:

Be it known that I, Paul P. Cret, a citizen of the United States, residing at Philadelphia, in the county of Philadelphia and State of Pennsylvania, have invented a new, original, and ornamental Design for a Table or Similar Article, of which the following is a specification, reference being had to the accompanying drawing, forming part thereof.

I claim:

The ornamental design for a table or similar article, substantially as shown.

PAUL P. CRET.
